UNITED STATES PATENT OFFICE.

JOHN STEC, OF WAPWALLOPEN, PENNSYLVANIA.

WINDOW-SHADE ROLLER.

Application filed March 9, 1923. Serial No. 623,912.

To all whom it may concern:

Be it known that I, JOHN STEC, a citizen of the United States, residing at Wapwallopen, in the county of Luzerne and State 5 of Pennsylvania, have invented certain new and useful Improvements in Window-Shade Rollers, of which the following is a specification.

This invention relates to window shade 10 rollers, and it has for a general object to provide an improved window shade roller of the spring type.

More specifically the invention has for 15 an object to provide a construction for the operating mechanism for the roller, which will render the same more certain in its action in holding the shade at any desired elevation.

For further comprehension of the invention, and of the objects and advantages 20 thereof, reference will be had to the following description and accompanying drawings, and to the appended claims in which the various novel features of the invention 25 are more particularly set forth.

Fig. 1 of the drawings is a longitudinal sectional view of a spring roller constructed according to my invention, indicating an ordinary shade in position thereon.

Fig. 2 is an end view thereof.

Fig. 3 is a transverse sectional view thereof, taken on the line 3—3 of Fig. 1.

Referring now to the drawing, the body 35 of the roller is in the form of a tube or elongated cylinder 10 having its ends closed by fixed heads 11 and 12 respectively, the head 11 being located inward a short distance from the end of the cylinder to provide a chamber 13 containing the clutch 40 mechanism. The roller is mounted to rotate on a fixed shaft 14 which passes freely through suitable apertures in the said heads 11 and 12. The shaft 14 has fixed thereon, about midway between its ends, a 45 circular block 15 and to this block is fixed one end of each of a pair of helical springs 16 which are coiled around the shaft on opposite sides of said block and are connected at their opposite ends with the heads 50 11 and 12 respectively, the connection being here shown as effected by passing the ends of the springs behind pins 17 fixed to the heads 11, 12.

Upon the end of the cylinder 10 closed 55 by head 12 a short drum 20 is fixed and

around this drum is coiled a cord 21 which has one end attached to the drum and its other end depending free and adapted to be engaged by the hand of the person lowering the shade. It is understood of course 60 that the shade, indicated at 22, is wound on the roller in correspondence to the winding of the cord 20 so that when the latter is pulled the shade is lowered.

The shade 22 is held in lowered position 65 by means of a novel form of clutch device which is constructed as follows: Mounted on the shaft 14 in the chamber 13 and adjacent the head 11 is a disk 25 which is freely rotatable on the shaft but held 70 against movement therealong. This disk has an annular flange 26 at its edge which is formed with internal ratchet teeth 27 engaged by a spring pressed pawl 28 on the head 11. This arrangement permits of free 75 rotation of the cylinder 10 in one direction with respect to this disk 25.

Feathered on the shaft 14 by an ordinary key and groove arrangement indicated at 29 with one face in contact with the disk 80 25 is a second disk 30 formed with a pair of apertures through which pass pins 31 extending parallel to the shaft 14, their opposite ends being connected by slot and pin connections 32 with the radial arms of 85 bell crank levers 33 which are fulcrumed to lugs 34 on the shaft 14 and whose other arms extend in a longitudinal direction and engage under spiral cams 35 formed on the radial wall of a drum 36 closing the chamber 90 13 in the cylinder in which the parts just referred to are located. This drum 36 has a cord 37 attached thereto and depending downward and adapted to be pulled to release the shade. 95

Formed in the disk 25 are apertures 40 adapted to register with the apertures in the disk 30 through which the pins 31 are inserted. The pins 31 are pressed into these apertures 40 by means of coiled springs 41 100 which surround these pins and bear between collars 47 fixed thereto and straps 43 having openings therein through which the pins pass. The disk 30 is pressed against the disk 25 by means of an expansion spring 44 coiled around the shaft 14 and having for an abutment a collar 45 fixed to the latter. The shaft 14 is formed with flattened ends 46 adapted to engage in vertical slots 47 in brackets 48 fixed to the window frame. 110

When the shade has been lowered, and the springs 16 tensioned, the roller is held against movement in a direction to raise the shade by reason of the engagement of 5 the pawl 28 on the head 11 with the ratchet teeth 27 on the disk 25. This disk 25 is held against rotation on shaft 14 both by means of the pins 31, and also by reason 10 of its frictional engagement with the disk 30. When cord 37 is pulled, and drum 36 rotated, the levers 33 are swung to first pull the pins 31 from the apertures 40 in the disk 25. The springs 41 being relatively 15 weak, the frictional engagement of the two disks is maintained until an additional movement of the pins 31 compresses the springs 41 substantially to their limits, whereupon the friction hold of the two disks on one another is decreased and the shade 20 moves upward.

Having thus described my invention what I claim as new and desire to protect by Letters Patent of the United States is as follows;

25 1. A window shade roller comprising a cylinder, a fixed shaft on which said cylinder is rotatably mounted, a spring in said cylinder adapted to urge it to rotate in one direction, and a manually releasable clutch 30 element adapted to hold said cylinder against rotation under the influence of said spring, said clutch element comprising a pair of disks in said cylinder adapted to frictionally engage one another, a ratchet and 35 pawl connection between one of said disks and the said cylinder, pins adapted to pass through registering apertures in the said disks to lock the latter to one another, levers connected to said pins, and means for 40 operating said levers.

2. A window shade roller comprising a

cylinder, a fixed shaft on which said cylinder is rotatably mounted, a spring in said cylinder adapted to urge it to rotate in one direction, and a manually releasable clutch 45 element adapted to hold said cylinder against rotation under the influence of said spring, said clutch element comprising a pair of disks in said cylinder adapted to frictionally engage one another, a ratchet and 50 pawl connection between one of said disks and the said cylinder, pins adapted to pass through registering apertures in the said disks to lock the latter to one another, levers connected to said pins, and means for 55 operating said levers, said means comprising a drum rotatably around the said shaft, and cam elements on said drum adapted to engage said levers.

3. A window shade roller comprising a 60 cylinder, a fixed shaft on which said cylinder is rotatably mounted, a spring in said cylinder adapted to urge it to rotate in one direction, and a manually releasable clutch 65 element adapted to hold said cylinder against rotation under the influence of said spring, said clutch element comprising a pair of disks in said cylinder adapted to frictionally engage one another, a ratchet and 70 pawl connection between one of said disks and the said cylinder, pins adapted to pass through registering apertures in the said disks to lock the latter to one another, levers connected to said pins, and means for 75 operating said levers, said means comprising a drum rotatably around the said shaft, and cam elements on said drum adapted to engage said levers, and a cord attached to said drum.

In testimony whereof I have affixed my 80 signature.

JOHN STEC.
